J. TELLIER.

DOBBY FOR LOOMS.

APPLICATION FILED SEPT. 25, 1913.

1,100,161.

Patented June 16, 1914.

UNITED STATES PATENT OFFICE.

JÉRÉMIE TELLIER, OF NEW BEDFORD, MASSACHUSETTS, ASSIGNOR OF ONE-HALF TO
DOLPHIS POIRIER, OF NEW BEDFORD, MASSACHUSETTS.

DOBBY FOR LOOMS.

1,100,161.

Specification of Letters Patent.

Patented June 16, 1914.

Application filed September 25, 1913. Serial No. 791,792.

To all whom it may concern:

Be it known that I, JÉRÉMIE TELLIER, a citizen of the United States, residing at New Bedford, in the county of Bristol and State 5 of Massachusetts, have invented certain new and useful Improvements in Dobbies for Looms, of which the following is a specification.

In my U. S. Letters Patent No. 1,052,768, 10 of Feb. 11, 1913, I have shown a doby for looms in which the latches are normally held out of the path of the actuator bar by springs and the latches are connected to the indicator levers by a novel arrangement of 15 rods and levers.

I have now found that the mechanism can be considerably simplified, and in accordance with my present invention I provide springs for normally holding the latches out 20 of the paths of the actuator bars as heretofore, and I provide latch-actuating rods which directly connect the latches with said indicator levers, thus dispensing with much of the mechanism heretofore employed.

25 In the accompanying drawings:—Figure 1 shows a vertical section through a doby embodying my improvements. Fig. 2 is a detail view, in perspective, showing how one of the upper latches is connected with its spring and with the rod which joins it with an indicator lever. Fig. 3 is a detail view, 30 in perspective, showing how one of the lower latches is connected with its actuating rod and with its spring, and how it is guided by 35 a suitably constructed grid.

The doby frame A, on which the several parts of the doby mechanism are supported, is of usual construction. The harness jacks B are pivotally supported as usual on a 40 transverse rod C and their pivotal movement is limited by a transverse bar D, in the usual way. Each harness jack has pivotally supported thereon a connector E, and to the upper end of each connector is pivotally attached an upper latch F, while a lower latch G is pivotally attached to the lower end of the connector, in the usual way.

The upper and lower actuator bars H and I, as heretofore, are guided in slots *a* formed 50 in the arms A' of the doby frame, and these bars are actuated by mechanism not shown but which may be of the ordinary kind. The indicator levers J are pivotally supported on a transverse rod K and normally rest at their outer ends on a strop bar 55

L, being separated and guided at their outer ends by vertical pegs l rising from the stop bar. The pattern cylinder M is of the ordinary kind, carrying radially arranged pegs m, and this cylinder may be actuated by any appropriate mechanism.

My improvements are applicable to the particular type of doby shown, and also to others having the same general characteristics.

The latches F are guided by a grid N and the latches G are guided by a grid O. Each latch F in the upper set of latches is connected with an appropriate indicator lever J by a rod P. This rod may be made of 70 wire, and it is looped at its lower end p and connected with a hook on the rear end of the corresponding indicator lever. At its upper end the rod is enlarged at p' and formed with an opening p² to receive the latch, the 75 construction being such that the rod will move the latch positively both upwardly and downwardly but will permit the latch to move through it freely in a horizontal direction.

In order to normally hold the latches out 80 of the path of the actuator bar, I provide springs Q. Each of said springs may be made of wire coiled around a horizontally arranged rod R, extending from one end of the doby frame to the other, and supported in brackets S, attached to the doby frame. One end of the spring Q is connected with the enlarged upper end p' of a rod P, while 85 the other end is engaged with another rod T, which may also extend from one side of the frame to the other. The construction and arrangement is such that the springs Q normally hold all the latches F out of the path of the actuator bar H, but when the 90 indicator levers J, to which the rods P are connected, are raised by the pattern cylinder the rods P will be pulled downward and thus positively move the latches into the path 95 of the actuator bar.

Each latch G of the lower set of latches is connected with an appropriate indicator lever J by a rod U, which is looped at its lower end and connected with the hooked end of an indicator lever. At its upper end the rod U is provided with a head u which is formed with an opening u' through which the latch G extends. Each head u is connected with a spring V, which is coiled around a rod W extending from one side of the frame 100

to the other, one end of the spring being connected at v with the head u and the other end v' of the spring being connected with the grid O , in the manner clearly shown in 5 Figs. 1 and 3. The arrangement is such that the latches of the lower set are normally held elevated out of the path of the actuator bar I . They may move horizontally freely in the heads u and they are directly connected with appropriate indicator 10 levers and are moved positively in both directions.

By my improvements the mechanism shown in my prior patent is very much simplified. 15

I claim as my invention:—

1. In a loom dobby, the combination with an actuator bar, the latches and indicator levers, of latch-actuating rods extending 20 directly from the indicator levers to the latches, directly connected therewith and provided with openings at their upper ends through which the latches extend, and springs connected with the dobby frame

directly connected with said latch-actuating rods for normally elevating said rods to hold the latches out of the path of the actuator bars.

2. In a loom dobby, the combination with an actuator bar, the latches and indicator 30 levers, of latch-actuating rods connected with the rear ends of the indicator levers and extending upwardly therethrough to the latches and thus directly connecting the indicator levers and latches, enlargements 35 on the upper ends of said latch-actuating rods having openings to receive the latches, and springs connected with the dobby frame and engaging said rods to normally hold the latches in an elevated position out of the 40 path of the actuator bar.

In testimony whereof, I have hereunto subscribed my name.

JÉRÉMIE TELLIER.
